TUBE CONNECTER CONSTRUCTION

Francis M. Pottenger, Jr., Monrovia, Calif.

Application December 8, 1930. Serial No. 500,827

2 Claims. (Cl. 215—73)

My invention relates to tubular connectors, particularly to the structural arrangement for insuring efficient connection between two co-acting tubular members, and more particularly my invention pertains to the construction of a resilient tubular member whereby it may telescopically engage a second relatively non-resilient tubular member such as the neck of a bottle and the like, and to project a vent tube therein.

10 My invention includes a resilient annular channel designed to sustain a vacuum therein and thereby engage a tubular surface with a suction-grip. An important feature of my invention is the divergent position of a side wall of the channel whereby exterior pressure on the wall is directed towards the engaged tubular surface rather than parallel with it, thereby increasing the efficiency of the engagement.

15 My invention also includes, where desirable, an integral vent tube, the wall of my connector being suitably strengthened to serve as a base for such vent tube.

20 Although my invention, obviously, may be employed in a wide range of devices, I shall, for the purpose of illustration and without implying any limitation as to its applicability, first describe my invention as embodied in the construction of a rubber connector of the type commonly used in medical practice to connect one or more rubber tubes to a flask or bottle for such purposes as administering intravenous injections and draining an empyema. I shall then describe my connector as applied to a flask for the purpose of drawing liquid therefrom, my connector in this 25 second case projecting a vent-tube into the flask to provide communication between the atmosphere and the space in the flask above the liquid level.

30 A rubber bottle-cap embodying my invention is of particular advantage for such a purpose, because it is simply constructed in comparison to the usual connector, and easily sterilized. There are no working parts to be lost, such as removable collars, bands, and screws, and having no 35 separate working parts, the connector may be manufactured at a relatively low cost.

35 The suction engagement of the connector with the neck of a flask is quickly made and quickly released and furnishes a positive joint that will resist considerable tension between the connector and the flask and is proof against any fluid leakage.

40 Other objects and advantages of my invention will be clear from the detailed description to fol-

low, considered with the accompanying drawings in which—

Fig. 1 is a fragmentary broken perspective view of my connector engaging a tubular member;

Fig. 2 is an enlarged sectional detail of the preferred form of my channel construction in which the lower channel wall is divergent;

Fig. 3 is a similar view of a modified form in which both channel walls are divergent;

Fig. 4 is a broken side elevation showing a connector assembled to a flask;

Fig. 5 is the bottom view of a connector showing in cross-section three tubes instead of two;

Fig. 6 is a vertical cross section of my connector incorporating an integral vent tube;

Fig. 7 is a bottom view of Fig. 6 with the outlet tube in cross section; and

Fig. 8 is a side elevation of the connector applied to a flask of liquid.

A rubber connector generally designated C is shown telescopically engaging a tubular member T, which may be, for example, the neck of a flask, as shown in Fig. 4.

Integral with the cylindrical wall 10 of the connector and preferably at the rim 11 thereof is an inwardly extending annular flange 12 which embraces the surface 13 of tubular member T. Preferably flange 12 is relatively thick laterally to prevent undue lateral flexure under external pressure.

Spaced below flange 12 and also integral with wall 10 is a second inwardly extending annular flange 14 preferably relatively flexible in comparison to flange 12 and diverging therefrom at an angle, as shown, to engage the surface 13.

Thus flanges 12 and 14 as sides define an annular channel, with the interjacent portion of wall 10 as the back, which will be hereinafter termed the "channel" and which, with the encompassed surface 13, forms a closed continuous annular space 16 capable of sustaining a vacuum.

The purpose of the angle at which flange 14 is positioned, one of the principle features of this invention, may be understood from Fig. 2. When there is a vacuum in the annular space 16, external pressure exerted against the channel presses the two sides of the channel against tubular member T, but is less effective against flange 14 than against flange 12, for the simple reason that such a wall is less easily flexed at an intermediate point than at its marginal edge—in this case, the rim 11. Moreover, pressure on flange 14 from below and within the connector may in some devices be less than the exterior atmospheric pressure against flange 12, as, for instance,

when the connector is used in a siphon-arrangement or as part of a pump.

To offset the disadvantages inherent in the location of flange 14, I place it at the angle shown 5 in order to increase its pressure against surface 13 by utilizing pressure exterior to the flange. Thus, while lateral pressure against flange 12, as indicated by the arrow in Fig. 2, is substantially parallel to surface 13 and is resisted only by the 10 inherent rigidity of flange 12, pressure against flange 14, on the other hand, is, because of the position of flange 14, directed at an angle towards surface 13, as indicated by the arrow, and serves to press flange 14 against surface 13 15 to make an efficient fluid-proof joint therewith.

In the modified form of the channel shown in Fig. 3, all parts are identical to the corresponding parts of Fig. 2, except the upper flange 17, which is designed like lower flange 14' of Fig. 3 20 or 14 of Fig. 2. In this case the efficiency of the engagement of the upper flange with surface 13 is increased, but it is not as easy to slip the channel over tubular member T as in the case of the preferred form.

The open end of a connector of the type illustrated is simply slipped over the neck of a flask, as shown in Fig. 4, and then to insure a vacuum within space 16, the back of the channel 15 is 25 squeezed inward and released. Fig. 4 shows a flask 18 capped by a connector C, carrying two tubes 19 and 20. In such an arrangement, common in medical practice, the liquid 21 in bottle 18 may flow out of the relatively long tube 20 and thereby set up a siphon action to draw liquid 30 upward through the relatively short tube 19. To dismantle such an arrangement the rubber connector C is simply "peeled" off the neck T of the flask. The number of tubes leading from cap C 35 may be increased for some purposes. Fig. 5 shows, for example, a cap having three tubes, 21, 22 and 23.

In Figs. 6, 7 and 8 is shown a form of my invention embodying a vent tube. The connector C" is similar to the previous form in having several 40 corresponding parts, namely, wall 10", rim 11" and a channel defined by inwardly disposed flanges 12" and 14" and wall portion 15" intermediate thereof. In addition, it has preferably a feature which may be embodied in any 45 of the forms, an inwardly disposed annular abutment flange 24 integral with wall 10" to serve as a stop for the rim 25 of a flask 26.

Integral also with wall 10" is an inwardly disposed vent tube 27 communicating with a vent 50 aperture 27a in the wall and preferably co-axial with the connector C". Preferably, this vent tube 27 has a wall thick enough to make it relatively rigid and wall 10" of the connector is relatively thick adjacent the base of the vent tube 55 to normally maintain the vent tube substantially parallel with longitudinal axis of the connector, if not co-axial with the connector.

The free end 28 of vent tube 27 extends sufficiently above the rim 11" of the connector to 60 permit a desirable level of liquid 29 in the flask and preferably free end 28 is bevelled so that any

liquid thereon tends to drain outward along the periphery of the tube.

One or more outlet tubes are provided, such as tube 30. Preferably, as seen in plan, tubes 27 and 30 overlap, as shown in Fig. 7, so that a portion 80 at 31 of the wall of tube 27 is in longitudinal alignment with and continuous with a portion at 32 of tube 30.

To employ this connector for the purpose of supplying a liquid through outlet tube 30, the liquid is first poured in flask 26, then connector C" is slipped over the neck 33 of the flask until rim 25 meets abutment flange 24. The wall of the connector may then be depressed at 15" to create a vacuum in annular space 16", but such a step may be omitted because handling in the act of slipping the connector over the neck of the flask ordinarily serves the same purpose. Finally the flask is inverted to the position shown in Fig. 8 and as liquid drains through tube 30, air 90 is admitted to the space above the liquid by means of vent tube 27.

It is to be understood that although the preferred forms of my invention have been described in specific detail, I nevertheless reserve 100 the right to all other embodiments and modifications properly within the scope of my appended claims.

Having described my invention, I claim:

1. The combination with a liquid-containing 105 flask having a cylindrical neck and an outwardly extending annular rim flange, of a flask-connector having in combination: a circular rubber wall telescoped over the neck of the flask in radially spaced relation to said flask rim flange; an 110 inwardly disposed annular rubber flange integral with said rubber wall embracing the flask neck; a second spaced inwardly-disposed annular rubber flange integral with said rubber wall and embracing the flask neck; an annular vacuum-sus- 115 taining space being defined by said wall, rubber flanges and the neck of the flask, said second rubber flange being relatively thin and inclined to such an angle that liquid pressure on one face augments the normal pressure of the flange 120 against the flask neck.

2. The combination with an inverted liquid-containing flask having a cylindrical neck and an outwardly extending annular rim flange, of a flask-connector having in combination: a circular rubber wall telescoped over said flask neck, the wall being of substantially larger inside diameter than the outside diameter of said flask flange; two inwardly-disposed annular rubber flanges integral with said wall embracing the 130 flask neck and maintaining said wall in spaced concentric relation to said flask flange, the rubber flange nearest said flask flange being inclined towards said flask flange, whereby said rubber flange along the edge of one of its faces 135 contacts the flask neck and is subjected on its opposite face to liquid pressure from within the flask, an annular vacuum-sustaining space being defined by said wall, rubber flanges and flask neck.
